UNITED STATES PATENT OFFICE.

SAMUEL A. CREELMAN, OF PORTLAND, MAINE.

CASH-RECORDER.

SPECIFICATION forming part of Letters Patent No. 765,378, dated July 19, 1904.

Application filed January 10, 1903. Serial No. 138,462. (No model.)

To all whom it may concern:

Be it known that I, SAMUEL A. CREELMAN, a citizen of the United States, residing at Portland, in the county of Cumberland and State 5 of Maine, have invented certain new and useful Improvements in Cash-Recorders; and I do hereby declare the following to be a full, clear, and exact description of the invention, such as will enable others skilled in the art to which 10 it appertains to make and use the same.

My invention relates to improvements in cash-Recorders of the class in which a continuous strip of paper is caused to cross an opening in the case, the paper being moved periodically by the opening of the drawer or other suitable mechanism, and my improvement particularly relates to means for moving the paper.

In the drawings herewith accompanying 20 and making a part of this application, Figure 1 is a plan view of my improved cash-recorder, and Fig. 2 is a sectional view showing in detail the mechanism for operating the paper.

In said drawings, A represents a case provided with a drawer B for the reception of 25 money or other articles. In the top of the case are paper-rolls, one, C, for blank paper, and the other, D, for receiving the paper after the record is made. These rolls may 30 be mounted in any convenient manner. For convenience the roll C is placed in front of the roll D. A toothed wheel F is secured to and rotates with roll D. The teeth on wheel F are concavo-convex and spaced apart a distance equal to the space it is desired to move 35 the paper each time the drawer is opened. The clutch member of the pivoted latch strikes against the convex side of the teeth as the drawer is pushed in and engages the concave 40 side as it is pulled out, rotating the wheel one tooth-space each time it is pulled out, but producing no movement of the wheel when the drawer is pushed in. In the top of the case is a writing-table G, which may be formed 45 integral with the case, as shown in Fig. 1, or in any convenient manner. As shown, it is formed by making two openings H and I in the case and passing the paper O up through one opening and down through the other; but 50 I do not intend to limit myself to this partic-

ular method of forming the table, it only being necessary that the paper pass over a narrow smooth surface which is exposed to receive the record. At a point below the toothed wheel and in the same vertical plane 55 a dog J is pivoted to the drawer. The position of the dog is such that when the drawer is pushed in it engages the front edge of one of the teeth on the wheel, whereby it is depressed until it passes beyond the tooth, when, 60 the dog end being the lighter, it passes up into the space between the teeth. Now when the drawer is opened the dog rotates the wheel one tooth-space, thus moving the paper over the table a distance determined by the distance 65 apart of the teeth on the wheel. A pawl K, pivoted to the case, engages the teeth on the wheel and prevents any backward movement thereof. For convenience in loading the paper-rolls and in removing the record the case 70 is provided with doors L and M, opening into the top thereof.

Having thus described my invention and its use, I claim—

1. In a cash-recorder, a suitable casing having two compartments one above the other, the upper compartment having two paper-holders rotatably mounted therein, a toothed wheel secured to and adapted to rotate one of said holders, a writing-table over which the 75 paper is drawn by the rotation of the holders and an opening in the bottom adjacent said toothed wheel, and the lower compartment having a suitable drawer adapted to slide therein and provided with a dog having its 80 clutch end lightest pivotally mounted in the side of the drawer and adapted to project upwardly through said opening in the bottom of the upper compartment and to engage said toothed wheel on the under side thereof when 85 the drawer is closed and to turn said wheel 90 one tooth-space each time the drawer is opened, whereby the paper is moved over the table a predetermined distance each time the drawer is opened. 95

2. In a cash-recorder, a suitable casing having two compartments one above the other, the upper compartment having two paper-holders rotatably mounted therein, a wheel provided with concavo-convex teeth spaced 100

apart a distance equal to the distance the paper is required to travel each time the drawer is opened, and the lower compartment having a suitable drawer adapted to slide therein and 5 provided with a dog having its clutch end lightest pivotally mounted in the side of the drawer and adapted to project upwardly through said opening in the upper compartment and to engage said toothed wheel on 10 the under side thereof when the drawer is closed and to turn said wheel one tooth-space

each time the drawer is opened, whereby the paper is moved over the table a predetermined distance each time the drawer is opened.

In testimony whereof I have affixed my ¹⁵ signature, in presence of two witnesses, this 8th day of January, 1903.

SAMUEL A. CREELMAN.

In presence of—

ELGIN C. VERRILL,
ALBERT F. MANN.
